US0D1000778S

(12) **United States Design Patent** (10) **Patent No.:** **US D1,000,778 S**
(45) **Date of Patent:** **** Oct. 10, 2023**

(54) **SHOE OUTSOLE BOTTOM**

(71) Applicant: **Skechers U.S.A., Inc. II**, Manhattan Beach, CA (US)

(72) Inventors: **Chase Greenberg**, Manhattan Beach, CA (US); **Abel Casas**, Lawndale, CA (US); **Tobin Dorn**, Manhattan Beach, CA (US)

(73) Assignee: **Skechers U.S.A., Inc. II**, Manhattan Beach, CA (US)

(**) Term: **15 Years**

(21) Appl. No.: **29/875,824**

(22) Filed: **May 10, 2023**

Related U.S. Application Data

(62) Division of application No. 29/862,218, filed on Dec. 7, 2022.

Primary Examiner — Rashida C. Walshon

(74) *Attorney, Agent, or Firm* — Marshall A. Lerner; Steven J. Kim; KLEINBERG & LERNER, LLP

(57) **CLAIM**

The ornamental design for a shoe outsole bottom, as shown and described.

DESCRIPTION

FIG. 1 is a bottom frontal-side perspective view of a shoe outsole bottom in accordance with my new design;

FIG. 2 is a top frontal-side perspective view thereof;

FIG. 3 is a left side elevation view thereof;

FIG. 4 is a right side elevation view thereof;

FIG. 5 is a front elevation view thereof;

FIG. 6 is a rear elevation view thereof;

FIG. 7 is a top plan view thereof; and,

FIG. 8 is a bottom plan view thereof.

The dash-dot-dash broken lines define the bounds of the claimed design and form no part claimed design. The faded portions form no part of the claimed design.

1 Claim, 7 Drawing Sheets
